Development Corporation, Inc., Wilmington,
Del., a corporation of Delaware

Application January 16, 1941, Serial No. 374,713

3 Claims. (Cl. 100—71)

This invention relates to presses, and in particular to press bodies having a cylinder with a reciprocable pressing plunger therein.

Heretofore, press bodies having a press cylinder had the press body and press cylinder cast as an integral unit so that the press could be used with a pressing plunger of a definite diameter only. Consequently, if with such a press work pieces were to be shaped which require only a pressure materially less than that obtainable by said pressing plunger, the press works highly uneconomically, not only because a great amount of energy is wasted but also because, in case a hydraulic press is used, the press works too slowly due to the time required for filling the large press cylinder. On the other hand, with the presses heretofore known it is not possible to exert a higher pressure than that which corresponds to the diameter of the pressing plunger pertaining to said press.

Accordingly, it is an object of the invention to provide a press body which will remedy the above mentioned drawbacks and will make it possible to use one and the same press body with a variety of pressing plungers of different diameters.

It is another object of the invention to provide a press body of the character referred to in the preceding paragraph, in which the press cylinder has fluid inlet and outlet means and is, together with said means, exchangeably mounted in the press body.

A further object of the invention consists in the provision of a press body having a hydraulically operable press cylinder-piston-assembly, in which the press cylinder may be replaced by a press cylinder of a different inner diameter, without affecting the fluid inlet and outlet means associated with the press body.

It is a still further object of the invention to provide a press body for a hydraulic press, in which the press cylinder has connected therewith fluid inlet and outlet means and may, together with said fluid inlet and outlet means, be replaced by another cylinder of a different inner diameter without changing the press body proper.

These and other objects and advantages of the invention will appear more clearly from the following specification in connection with the accompanying drawing, in which:

Figure 1 shows an embodiment of the invention in connection with a pressing plunger of relatively small diameter.

Figure 2 is a section along the line 2—2 of Figure 1, but with a slightly different sized press cylinder and plunger therein.

General arrangement

According to the present invention the press body has a press cylinder which, in contrast to the conventional designs, is not integral with the press body but is inserted therein and may be exchanged with press cylinders having the same outer diameter but a different inner diameter for receiving a different sized press plunger.

According to one embodiment of the invention the insertable press cylinder has connected thereto fluid inlet and outlet means so that removal of the exchangeable press cylinders will simultaneously remove the fluid inlet and outlet means.

Structural arrangement

Referring first to Figure 1, the press body shown therein comprises a press head 10 and a press bed 11 connected with each other by side elements 100 having strain rods 12 and nuts 13. 15 The side elements each have guiding apertures or slots 101 into which slidably fit the flanges 102 of the platen 31.

Provided in the press head 10 is a bore 14 in which is exchangeably mounted a press cylinder 15. The press cylinder 15 may be connected with the press head 10 in any convenient manner, for instance by screws 16 and, to this end, is preferably provided with a flange 17. The upper portion of the press cylinder 15 has a chamber 18 into which extends a surge valve 19 connected in any convenient manner with the press cylinder body 15. The surge valve 19 is provided with a baffle plate 20 to prevent the fluid escaping from the press cylinder through the surge valve from splashing to the top and side walls of the fluid storage or surge tank 21 mounted on top of the press head 10.

Reciprocably mounted in the press cylinder body 15 is a press piston 22 with an advancing area 23 and a retraction area 24 which latter is formed by the difference in diameter of the press piston 22 and the piston shaft 25 connected to the piston 22.

To prevent leakage between the press cylinder 15 and the piston shaft 25, packing material 26 compressed by a gland 27 is provided at the lower end of the press cylinder body 15. The lower end of the piston shaft 25 is connected in any convenient manner, for instance by connecting discs 28 and 29 and screws 30, with a platen 31 which may be guided by gibbs or any other convenient means in the usual manner in the press body.

The press platen 31 is provided with bores 32 through which pass rods 33 having their lower ends connected with a yoke 34 carrying an ejector

35. The rods 33 are guided in eyes 36 and 37 and may be provided with collars 38 and 39, or with cams in the conventional manner for controlling any mechanism associated with the press. The rods 33 are suspended in the platen 31 by means of nuts 33a.

The upper and lower ends of the press cylinder body 15 communicate with conduits for alternately admitting and exhausting fluid to and from the press cylinder.

Provided in the press head 10 is furthermore a channel 42 communicating with the surge tank 21 and adapted to be connected with conduit means for admitting fluid to or withdrawing fluid from said surge tank. 44 is a bolster plate in the press bed for receiving the lower die or the work piece.

The press operates in the usual manner. When fluid is withdrawn through conduit 41, the press piston 22 with the piston shaft 25 moves downwardly by gravity, while the surge valve 19 admits fluid from the surge tank 21 to the space above the piston 22. Simultaneously, fluid is introduced from a fluid source through conduit 40 into the space above the piston 22.

When the press platen 31 engages a work piece, pressure builds up in the space above the piston 22 so that the surge valve 19 closes. The surge valve 19 does not form a part of the present invention and for a more detailed description thereof reference may be had to the U. S. Patent No. 2,193,248, issued March 12, 1940, to Walter Ernst. When the pressing stroke is completed, fluid is withdrawn from conduit 40 and admitted to the retraction area 24 through conduit 41 so that the piston 22 with piston shaft 25 and platen 31 moves upwardly. When the platen 31, during its retraction stroke has reached a predetermined point of travel the ejector 35, by means of the rods 33 and yoke 34, will have been lifted to such an extent that it has passed the bolster plate 44 and ejected the work piece.

The press consists of two sub-assemblies which may be assembled according to the desired tonnage at the factory. The first sub-assembly consists of a press bed 11, side elements 100, strain rods or other fastening means and press platen 10. These are assembled with the flanges 102 of the platen in proper position in the slots or apertures 101. The other sub-assembly consists of the press head 10 having a standard inside bore, the cylinder body 45 having a standard outside diameter substantially the same as the inside diameter of the press head so as to fit within the standard inside diameter of the presshead, and having an internal bore and a piston 22 fitting therein.

In order to construct a press of the desired tonnage, the elements constituting the first assembly are assembled together, the elements being of the proper dimensions. The elements forming the second sub-assembly vary as to the cylinder and piston, i. e., a cylinder and its corresponding piston are selected having the proper diameterd piston and cylinder bore, which will provide a press of the desired tonnage, and these are assembled with the standard press head 10 and the flange 17 by screws 16 as heretofore stated, to make up the second sub-assembly. This second sub-assembly is connected to the first sub-assembly by placing the press head with its previously assembled cylinder and piston onto the side elements. The fastening means, such as the strain rods 12 and nuts 13 are connected to the press head and the platen connected to the

end of the piston by screws 30 in any order desired.

The surge tank 21 and surge valve 19 with baffle plate 20 may be assembled at any time, either during the assembly of the second described sub-assembly or after the first and second sub-assemblies have been connected to each other.

Each sub-assembly is separately made up and 10 they are then connected together as stated, preferably at the factory.

By providing the press heads 10, 51 with a plurality of exchangeable cylinder bodies 15 and 45, only one single press body is required for economically performing a plurality of different pressing operations which require different power and which heretofore could be economically carried out only with a plurality of complete presses.

It will be understood that we desire to comprehend within our invention such modifications as come within the scope of the claims and the invention.

Having thus fully described our invention what we claim as new and desire to secure by Letters Patent, is:

1. A press comprising a bed, said bed having spaced side elements extending vertically from said bed, a press platen slidably mounted between the side elements, said bed, side elements and press platen constituting a sub-assembly; a press head having a main bore therein constructed to a standard inner diameter, a cylinder body having an internal bore and a standard external diameter substantially the same as the inner diameter of said press head, said body being disposed within the bore of said press head, means for detachably connecting said cylinder to said head, a piston located within said internal bore of said cylinder body and provided with a piston rod, said piston rod being provided with means for detachable connection with said press platen; said press head, cylinder body, piston and piston rod constituting an additional sub-assembly; said second named sub-assembly being disposed 45 on top of said first named sub-assembly, means attaching said side elements to said base and said press head to said side elements; whereby in the assembly of said second named sub-assembly one of several cylinders of differently sized 50 internal diameter but of the same external diameter and a piston to fit said cylinder bore may be positioned within the bore of said press head, thereby to effect a press of desired tonnage, said side members further having means for guiding 55 said platen and positioning the same relative to said piston to facilitate alignment of the platen and piston during the assembly of said first named assembly and said second named assembly.

2. A press comprising a bed, said bed having 60 spaced side elements extending vertically from said bed, a press platen slidably mounted between the side elements, said bed, side elements and press platen constituting a sub-assembly; a press head having a main bore therein constructed to a standard inner diameter, a cylinder body having an internal bore and a standard external diameter substantially the same as the inner diameter of said press head, said body being disposed within the bore of said press head, means 65 detachably connecting said cylinder to said head, a piston located within said internal bore of said cylinder body and provided with a piston rod, said piston rod being provided with means for detachable connection with said press platen; 70 said press head, cylinder body, piston and piston rod constituting an additional sub-assembly; said press head, cylinder body, piston and piston rod 75 constituting an additional sub-assembly; said second named sub-assembly being disposed on top of said first named sub-assembly, means attaching said side elements to said base and said press head to said side elements; whereby in the assembly of said second named sub-assembly one of several cylinders of differently sized internal diameter but of the same external diameter and a piston to fit said cylinder bore may be positioned within the bore of said press head, thereby to effect a press of desired tonnage, said side members further having means for guiding said platen and positioning the same relative to said piston to facilitate alignment of the platen and piston during the assembly of said first named assembly and said second named assembly.

rod constituting an additional sub-assembly; said second named sub-assembly being disposed on top of said first named sub-assembly, means attaching said side elements to said base and said press head to said side elements; whereby in the assembly of said second named sub-assembly one of several cylinders of differently sized internal diameter but of the same external diameter and a piston to fit said cylinder bore may be positioned within the bore of said press head, thereby to effect a press of desired tonnage, said

10

side members further having means for guiding said platen and positioning the same relative to said piston to facilitate alignment of the platen and piston during the assembly of said first 5 named assembly and second named assembly, said attaching means including a plurality of strain rods having fastening means at each end thereof for engaging said base and press head.
